UNITED STATES PATENT OFFICE.

GEORGE T. LADD, OF PITTSBURGH, PENNSYLVANIA.

BOILER.

1,283,814.

Specification of Letters Patent.

Patented Nov. 5, 1918.

Application filed February 28, 1916. Serial No. 80,948.

To all whom it may concern:

Be it known that I, GEORGE T. LADD, residing at Pittsburgh, in the county of Allegheny and State of Pennsylvania, a citizen 5 of the United States, have invented or discovered certain new and useful Improvements in Boilers, of which improvements the following is a specification.

It is characteristic of vertical water tube 10 boilers now in use that the combustion chamber is so constructed and connected to the chamber in which the drums and tubes are arranged, that the products of combustion are directed or delivered into the tube 15 or heating chamber in such manner that they will impinge against the tubes at or adjacent to the lower ends of the first set of tubes and flow up along the same, and in a comparatively narrow passage between said 20 tubes and the wall of the setting to a point adjacent to their upper ends where such products flow transversely of the tubes and down along the second set of tubes. As the gases will contact with the relatively 25 cold tubes of the first set, combustion, which is incomplete in the combustion chamber, will be checked, and gradually diminish as the gases move up along said tubes.

The invention described herein has for its 30 object a construction of fire or combustion chamber which will permit of a sufficient movement of the gases as to insure a practically complete combustion prior to the products of combustion encountering the 35 tubes, in combination with an arrangement of baffles whereby the most efficient heating of the first series of tubes will be due to gases moving down along such tubes after practically complete combustion has been 40 effected. The invention is hereinafter more fully described and claimed.

In the accompanying drawings forming a part of this specification, Figure 1 is a partial sectional elevation of a vertical 45 water tube boiler embodying my improvements; Fig. 2 is a sectional elevation on a plane indicated by the line II-II Fig. 1; Fig. 3 is a sectional plan on a plane indicated by the line III-III Fig. 1.

50 In the construction shown in Figs. 1 and 2, the boiler consisting of an upper drum 1 and a lower drum 2 and three sets or series of tubes 3, 4 and 5 connecting said drums, is inclosed on the rear and sides with suitable 55 walls as is customary. In lieu, however, of arranging the upper portion of the front

wall a short distance from the boiler and supporting the lower end of such wall on the inner end of the arch forming the top of the fire or combustion chamber, as has 60 heretofore been the practice, the side walls in my improved construction are extended a distance equal to the desired depth of the fire box or combustion chamber, and the extended ends of the side walls are con- 65

nected by the front wall of the setting which also forms the front wall of the fire chamber. As the top of this fire or combustion chamber preferably coincides as regards position with the top of the boiler setting, 70 there is provided a chamber having a height measuring from the grate bars or point of introduction of the fuel equal or approximately equal to the length of the tubes connecting the upper and lower drums, the 75 gases generated on the burning of the fuel, can expand freely and become thoroughly intermingled as they rise, and combustion will be substantially complete. The up- 80

ward movement of the gases is not due to 85 their low specific gravity alone, but also to the draft in the stack as the outlet from the combustion chamber is adjacent to the upper end of the latter. As the first series of tubes 3 is wholly to one side of the natural upward line of flow of the gases, the latter, in their upward movement will 90 not be cooled by contact with the tubes, or only to a slight extent. These tubes being cooler than the gas, a partial vacuum is 95 formed around and adjacent thereto, so that the hot gases will be drawn down from the upper portion of the combustion chamber and flow down along and between the tubes into space 6 between the first series of tubes 3 and the baffle 7 which is arranged to prevent gases passing from the space 6 between the set of tubes 4. The gases moving in this reverse direction will pass out between the lower portions of the tubes 5 and 100 mingle with the gases flowing upward in the combustion chamber, thus producing a reverberatory movement of the products of combustion in the combustion chamber.

In the construction of boiler furnaces in 105 general use whatever heat is absorbed by the walls of the combustion chamber are merely radiated from the sides and front end back into the chamber, but in the construction shown herein, the heat absorbed 110 by the front wall of the combustion chamber is radiated toward the tubes 3, and the sur-

face of said wall will also reflect the heat toward said tubes.

The heat and products of combustion escape from the upper portion of the combustion chamber passing through between the upper portions of the tubes 3 over the baffle 8 and down along the set of tubes 4 and the space 9 between the tubes 4 and the vertical baffle 10. The products of combustion flow from between the lower portions of the tubes 4 and the lower end of the space 9 under the baffle 11 and up along the tubes 5 to the stack.

It is preferred to so construct the front of the combustion chamber as to provide an open-topped pocket 13 for the reception of superheater elements 14. The upper end of this pocket is connected by an opening 15 with the upper end of the combustion chamber, so that products of combustion may flow down through the pocket in contact with the superheater elements and into the combustion chamber through openings 16 in the curtain wall 17 forming the inner wall of the pocket.

In an application filed of even date herewith I have described and claimed the combination of superheaters with the walls of combustion chambers of boilers for the purpose of protecting such walls against excessive heating and also for preventing loss of heat by radiation from such walls. While the benefits derived from such use of superheaters will be great, regardless of the specific construction of combustion chamber, such benefits will be much greater when a high combustion chamber is employed as herein described and shown.

It will be observed that the baffle 7 is so arranged that the gases in their downward movement in the combustion chamber may pass entirely through the first set or series of tubes 3, and enter an unobstructed space 6 in the rear of such set and flow down through the same to the surface of the lower drum by which the gases are deflected out into the combustion chamber. In thus providing a space in the rear of the set of tubes 3, the oppositely flowing streams of gases, upward in the combustion chamber and downward in the space in the rear of set of tubes 3, can move freely without interfering the one with the other.

In the constructions heretofore employed the hot gases were forced directly against the lower ends of the first set or bank of tubes. By reason of the high speed imparted to the gases due to the confined space through the gases were drawn, the gases would injuriously affect the lower of the first bank of tubes. In the improved construction, the chamber in which combustion occurs being extended upwardly with its horizontal dimensions practically equal to the area of the grate, nearly to the upper

ends of the first bank of tubes, the gases are free to move up parallel with the first bank of tubes, and their lateral movement toward the tubes will be due solely to expansion and not to the pull of the stack. The lower portions of the first bank or set of tubes are protected from direct cutting impingement of the gases, by those gases, which as heretofore stated flow down along the first set of tubes and through the chamber 75 and are deflected outward transverse of the lower ends of the first set of tubes and into the combustion chamber by the lower drum. This outward movement of the gases will tend to push the extremely hot gases in the combustion chamber from the tubes.

After passing over an inclosed baffle 8 which closes the upper end of the space 6, the gases flow down along the tubes of the intermediate set 4 and the uninterrupted space 9 between the set of tubes 4 and the substantially vertically baffle 10 extending down from the upper drum in a plane adjacent to the front tubes of the rear set 5, to a point a short distance above the lower drum. The gases flowing upwardly along the outer wall of the combustion chamber, will be deflected by the top of said chamber toward the throat between the upper drum and the baffle 8, in a state of complete combustion. All the gases entering the space 9 are caused to flow around baffle 11 at the lower end of space 9 in among the lower portions of the intermediate set of tubes, transversely of the lower portions of the tubes of set 5 and up 100 along the same to the outlet 12 to the stack.

It is characteristic of my improvement that no material portions of the products of combustion contact with the tubes until after opportunity for practically complete combustion has been afforded, and that the gases which pass through the throat above baffle 8 have either not been in contact with the tubes of set 3 or have been regenerated by passing through the combustion chamber 110 after contact with tubes of set 3.

It will be observed that the space 6 is protected by the baffle 8 from the direct pull of the draft, so that the hot gases having passed through the first set of tubes near their upper ends, will be practically free to move down through such space in which the pressure has been reduced by the cooling effect of the tubes. In effect, the baffles 7 and 8 form the rear walls of a combustion chamber through which the first set or bank of tubes, or in which the major portions of such tubes are so arranged that gases may pass through and beyond such set of tubes.

I claim herein as my invention:

1. The combination, with a boiler consisting of an upper and a lower drum, and a plurality of sets or banks of vertical tubes connecting the drums, of a baffle extending from the lower drum along the front tubes 130

of the intermediate set or bank, and extending across the space between the first and intermediate sets of tubes a short distance below the upper drum, and a fire box or combustion chamber having its top above the portions of the baffling across the space between the first and intermediate sets of tubes, and of substantially uniform width for its entire length.

10 2. The combination with a boiler consisting of an upper and a lower drum, and a plurality of sets or banks of vertical tubes connecting the drums, of a combustion chamber or fire box having a height approximately equal to the distance between the upper and lower drums, and of substantially uniform width, a baffling extending upwardly from the lower drum and so located that the first set of tubes will for a major portion of their length be wholly within the fire box or combustion chamber.

15 3. The combination, with a boiler consisting of an upper and a lower drum and a plurality of sets or banks of vertical tubes

connecting said drums, of baffles arranged to 25 cause products of combustion to move across such sets of tubes at points adjacent to the ends thereof, and at points intermediate the end traverses, and a combustion chamber or fire box having a height not less than that 30 of the first baffle, and a substantially uniform width.

4. The combination, with a boiler consisting of an upper and a lower drum and three sets of banks of vertical tubes connecting 35 said drums, of baffles arranged to cause products of combustion to move across such sets of tubes at points adjacent to the ends thereof, and at points intermediate the end traverses, and a combustion chamber or fire 40 box having a height not less than that of the first baffle, and a substantially uniform width.

In testimony whereof, I have hereunto set my hand.

GEORGE T. LADD.

Witness:

G. G. TRILL.
